UNITED STATES PATENT OFFICE.

WILLIAM A. CORNBROOKS, OF MOLINE, ILLINOIS, ASSIGNOR TO WILLIAMS, WHITE & COMPANY, OF MOLINE, ILLINOIS, A CORPORATION OF ILLINOIS.

PUNCHING-MACHINE.

1,150,851.

Specification of Letters Patent. Patented Aug. 24, 1915.

Application filed March 3, 1915. Serial No. 11,667.

To all whom it may concern:

Be it known that I, WILLIAM A. CORNBROOKS, a citizen of the United States, and a resident of Moline, in the county of Rock Island and State of Illinois, have invented 5 certain new and useful Improvements in Punching-Machines, of which the following is a specification, reference being had to the accompanying drawings.

10 In the construction of cylindrical metal structures such, for example, as large tanks and stacks, it is necessary to form the same of a plurality of annular sections, each such section being composed of a plurality of 15 heavy plates properly curved and riveted end to end. These annular sections telescope one within another sufficiently far to permit of their being riveted together, and consequently each section is constructed 20 slightly larger in diameter at one end than at the other. This makes it necessary that the rivet holes along the edge of the larger end shall be spaced very slightly farther apart than at the other end, in order that 25 they may properly register with the rivet holes in the smaller end of the next-adjacent section. The rivet holes are, of course, always punched along the edges of the plates before leaving the mill, and as heretofore 30 performed, this punching operation has been a comparatively slow, tedious and expensive one, due to the fact that each plate has required four separate settings and handlings in order to punch the two end rows and two 35 side rows of rivet holes,—the spacing-devices that regulate the distance between the holes that will be formed as the plate is moved intermittently through the punching machine having to be very carefully and 40 finely adjusted after punching the holes along one side edge of the plate before the punching of holes at the opposite side is commenced, in order that there may be produced the required difference in spacing be- 45 tween the holes along one edge and those along the opposite edge.

The leading object of my invention is to provide a plate-punching machine with means that while permitting the simultaneous punching of the rows of holes along the opposite side margins of a plate, will also cause a slight relative movement, after every punching operation, between the plate being punched and one of the punching 55 mechanisms, such slight movement be-

ing in addition to the regular intermittent movement of the plate through the machine, which slight additional relative movement will result in the holes of one of such rows being differently spaced apart than are the 60 holes in the other row.

It is also one of the objects of the invention to so construct and arrange the punching devices as to avoid the necessity of more than one handling and setting of a plate in 65 the machine.

I accomplish these objects by the devices and combinations of devices shown in the drawings and hereinafter described.

That which I believe to be new will be 70 pointed out in the claims.

In the drawings,—Figure 1 is a front elevation of a punching-machine with my improvements applied thereto; Fig. 2 is a side elevation of the machine shown in Fig. 1; 75 Fig. 3 is an enlarged detail, being a vertical section taken at line 3—3 of Fig. 1; Fig. 4 is a vertical cross-section through the upper and lower bolsters that carry the punching means and dies therefor, respectively, 80 showing applied to such bolsters a plurality of punching members and dies adapted to punch at each operation a plurality of holes longitudinally of a plate instead of a single hole as in the construction shown in Figs. 1, 85 2 and 3; Fig. 5 is an end view of the parts shown in Fig. 4; Fig. 6 is a modification, being a side elevation of manually-operated means for moving the punching mechanism, which may be substituted for the automatic 90 means for the same purpose shown in Figs. 1 and 2; Fig. 7 is a front view of the parts shown in Fig. 6; Fig. 8 is a plan view of the lower or die-carrying bolster, and showing, 95 also, a portion of the mechanism for moving the bolster; Fig. 9 is a plan view of a portion of a plate showing the holes as punched therein by the punching means of Figs. 1 and 3; and Fig. 10 is a similar view showing on a plate the holes as formed 100 when the multiple punching means of Fig. 4 are employed to punch the longitudinal rows of holes.

In the several figures of the drawings, in which corresponding parts are indicated by 105 like reference characters—15, 16 and 17 indicate, respectively, the side bars, the top cross-bar and the lower cross-bar that together constitute the supporting framework of a well-known type of punching-machine 110

employed for punching heavy plates and the like.

18 indicates the operating shaft, suitably journaled in the framework of the machine and driven and controlled by any suitable means, not necessary to here describe.

19 indicates a ram that is movable up and down in guides on the side bars 15 of the frame, the reciprocation of such ram being effected through eccentrics on the shaft 18 with which are connected pitmen 20 pivoted at their lower ends to the ram.

21 indicates a cylinder mounted on the top cross-bar 16 of the frame, in which cylinder 15 works an air-cushioned piston, to the stem of which are attached two connecting-rods, one of which is shown in Fig. 1 and indicated by 22, said rods being connected to opposite sides of the ram 19,—such devices forming 20 an ordinary pneumatic counterbalance.

The parts so far mentioned are of well-known construction, and need no further detailed description.

23 and 24 indicate the upper and lower 25 bolsters that carry, respectively, the punches and the dies that coöperate with such punches. Such bolsters are of ordinary construction, except that instead of being rigidly affixed to the under face of the ram 19

30 and the upper face of the usual table 25, respectively, they are so attached as to be movable horizontally with respect to such members 19 and 25, such movement being, in the construction shown, a swinging or

35 turning movement on pivots 26 and 27,—the pivot 26 being on the upper face of the bolster 23 and entering a suitable opening in the lower face of the ram 19 and the pivot 27 depending from the bolster 24 and entering

40 an opening in the table 24 (see Fig. 1). The two pivots are in alinement and are located, in the construction shown, near one end of the bolsters and directly beneath the punching means, hereinafter described, that 45 forms one of the longitudinally-extending rows of holes in a plate.

In order to permit the required swing of the bolsters on their respective pivots, the securing-bolts employed for attaching the 50 bolsters to the ram and table, respectively, pass through suitable slots. Such construction is clearly shown in Fig. 3,—the bolts for securing the upper bolster to the ram being indicated by 28 and the slots by 29, such slots being formed in the wide head 30 extending at both sides of the web or body-portion of the ram 19.

31 indicates the securing-bolts for the 60 lower bolster, and the slots referred to through which they pass are formed in such bolster and are indicated by 32.

33 indicates pilot-pins affixed to one of the bolsters,—the upper one in the construction shown,—and movable in suitable openings in 65 the other bolster. These pins 33 maintain

the bolsters at all times in proper relative position so as to insure the punches and dies carried by them being always in alinement.

34 indicates a series of punch-holders which, as shown, are movably secured to the under face of the upper bolster by two rows of bolts 35 extending into T-shaped slots in the bolster, as usual, the punches carried by the holders being indicated by 36.

37 indicates a gag, one being ordinarily provided for each punch, each gag being in the form of a sliding bar which is adapted to extend over the head of one of the punches and thus hold that punch in operative position, but which may be withdrawn to render such punch inoperative, as is well understood. Such series of gags, in the arrangement shown, is effective with relation to all of the punches 36 shown in Fig. 1, except the two end punches, gags being omitted for those end punches for the reason hereinafter set forth. The front edge of each gag is provided with a vertical pin 38 (see Fig. 3) that passes through an opening in a bar 39 extending transversely across the front of the machine, and such bar 39 is connected to a rock-shaft 40 through links 41, such links being made fast at their upper ends to the rock-shaft. The links should be somewhat loosely connected to the bar 39 in order not to impede the turning of the bolsters on their pivots.

42 indicates bearings for the rock-shaft, such bearings being secured to the ram, and 43 indicates operating handles, one at each 100 end of the rock-shaft.

43^a indicates the dies, one for each punch, their holders 43^b being secured in the usual manner to the upper face of the lower bolster 24.

The means for automatically effecting a slight turning movement of the bolsters on their pivots between successive punching operations comprises, in the construction shown, a train of gears arranged and operating as follows: On one end of the shaft 18 is secured a disk 44 having a tooth 45 suitably secured in a hole in the periphery of the disk. A series of tooth-holding holes 46 is shown so that a plurality of teeth may be employed, if required. 47 indicates a gear of the face-wheel type, with which the tooth 45 engages, said face-wheel 47 being secured on the end of an upright shaft 48 journaled in brackets 49 and 50 secured to the adjacent side member 15 of the framework.

On the lower end of the vertical shaft 48 is a worm 51 that has engagement with a worm-gear 52 mounted on a short shaft 53 journaled in an extension 54 of the bracket 60, said shaft 53 having secured to its outer end a pinion 55 that meshes with an idler-gear 56 that is journaled on an adjustable stud carried by an arm 57 that is adjustably mounted on the end of a bar or

long bolt projecting from and secured to the supporting frame member 15. The idler-gear also is in mesh with another gear 58 secured on the end of a short shaft 59 suitably journaled in a bracket 60 affixed to the said frame member 15. 61 indicates a small beveled gear loose on the shaft 59 but adapted to be connected therewith through a clutch-member 62 that is slidingly secured 5 on the shaft and adapted to be moved into engagement with a properly-shaped hub of said beveled gear 61. 63 indicates another beveled gear in mesh with the gear 61; said beveled gear 63 being fast on a shaft 64 arranged at right angles to the shaft 59 and suitably journaled in a bracket 65. On said last-named shaft is a worm 66 that meshes with a worm-gear 67 carried at the adjacent end of the lower bolster 24. It will be readily understood that gearing, such as described, interposed between the shaft 18 and the bolster 24 will cause but a very slight turning of the bolsters on their pivots, and such turning will occur intermittently only, 10 owing to the character of the engagement between the disk 44 and the face-wheel 47. The extent of the turning of the bolsters may be increased, of course, where required, by providing one or more additional teeth 45 in the holes 46 of the disk 44, or variation in the speed of the driving means may be effected by substituting different sizes of spur-gears for some of those shown: 15

In operation, with the machine provided with a single row of punches extending from side to side of the machine; as clearly shown in Fig. 1, before any punching is done the bolsters are to be turned on their pivots so that the row of punches and dies will extend in a slightly diagonal direction across a plate that may be entered in the machine in the usual manner. Such adjustment of the bolsters, preliminary to the first punching operation, may be readily accomplished by hand by shifting the clutch-member 62 out of engagement with the hub of the beveled gear 61 and then, by applying a hand crank to the squared end of the shaft 64, turning such shaft to cause such shifting of the bolsters by reason of the engagement of the worm 66 with the worm-gear 67 on the lower bolster. After the bolsters have been thus shifted to bring the punches and dies into such diagonal relation with a plate, the clutch 62 is to be again moved into clutching engagement with the beveled gear 61 so that thereafter the train of gears will automatically act to very slightly move the bolsters between successive punching operations. The row of punches and their dies being set as described, the first descent of the ram will cause a row of holes to be punched in the plate adjacent to the leading edge thereof, as clearly indicated by the transverse line of holes in the 20 plate shown in Fig. 9. The plate there shown and in Figs. 1 and 2 is indicated by A. Upon the completion of the diagonal row of holes mentioned, the gags 37 that extend over the heads of all of the punches between the end ones are withdrawn, and thereafter all of such intermediate punches are inoperative during the punching of the rows of holes along the sides of the plates. The holes in each of the side rows are successively punched by the end punches as the plate, attached to an ordinary spacing-carriage (not shown) by the usual grippers 68, is advanced through the machine. As hereinbefore explained, when these plates are designed for use in the construction of annular structures, such as tanks, stacks and the like, it is necessary that the holes on that end of a section of the structure that receives within it the smaller end of another similar section should be spaced slightly farther apart than are the holes in the smaller end of the entering section, in order that the two annular rows of holes may properly register for the reception of the 25 securing rivets. By my improvements the different spacing of the two longitudinal rows of holes in a plate is thus accomplished. Assume that the holes of one row are to be two inches apart and that to secure proper results in the way of registry of holes, when two curved telescoping sections are to be riveted together, the holes in the other row should be, say, two and one sixty-fourth 30 inches apart. The spacing-carriage that moves the plate will be caused to advance the plate just two inches between successive punching operations, and the punching means comprising the punch that is in line with the bolster pivots will punch such holes two inches apart. The means for punching the other row of holes, comprising the punch near the opposite end of the bolster 23, will be advanced one sixty-fourth of an inch 35 after each punching operation, due to the movement of the bolsters imparted by the train of gears, as hereinbefore described. Such gearing acts directly upon the lower or die-carrying bolster, but, as before explained, both bolsters necessarily turn in unison by reason of their being connected together by the pilot-pins 33. By the time the punching of the holes has proceeded to a point midway of the length of the plate, the bolsters will have been gradually turned on their pivots sufficiently to bring them to a position where they extend directly across the plate—in other words, at right angles to the side edges of the plate—and thereafter the diagonal position of the bolsters will be again assumed, but, as will be understood, in a reverse direction, and the angle will increase at each movement until the end of the plate is reached. When such end is reached, the gags that had been with- 40

drawn from over the heads of all the punches intermediate the end ones will be inserted in place, thus making all of such punches operative and thereby producing on the 5 last stroke of the ram a row of holes at the end of the plate that extends diagonally to the same extent, but in a reverse direction, as the row at the other end.

In Figs. 4 and 5 I have illustrated a modification with respect to the means for punching the rows of holes along the side edges of the plate, wherein such punching means comprises a plurality of punches at each end of the upper bolster. These punches, five in 10 number in the construction illustrated, and indicated by 36^a, are supported in a holder 34^a, being adjustably secured therein so as to be spaced apart as desired. The dies and die-holders in said Figs. 4 and 5 are indicated by 43^c and 43^d, respectively. The punch and die-holders extend transversely of the bolsters, and take the place, as stated, of the end punches and dies in the row shown in Fig. 1. With such modified construction the plurality of punches and the dies coöperating therewith will, at one end of the bolster, be spaced apart a certain distance and at the other end will be spaced at a slightly different distance apart; for example, the punches at the pivoted end of the bolster may be set at two inches apart and those at the opposite end at two and one sixty-fourth inches apart. As in the construction hereinafter described, the 20 bolsters for the first punching operation will be set diagonally and with the transverse row of punches covered by their gags, so that on the first punching stroke the required diagonal end row of holes will be formed, except the hole at each end. During this operation, the punches 36^a will be rendered inoperative by the withdrawal of the gag 37^a (see Fig. 5). The plate is then to be adjusted so as to bring the end punching means in proper position that upon the 25 second punching operation one of the end holes punched by each of the said multiple punching means of Figs. 4 and 5 will form a continuation of the diagonal end row. On the start of such second punching operation, the gags 37 will, of course, be drawn out and the gags 37^a pushed in. Thereafter the holes punched along the side edges of the plate will be in blocks of five, 30 as indicated on the representation of a portion of a plate in Fig. 10—the plate there being indicated by A'. After each such punching operation, the gearing will be set in motion, as before described, and the bolsters given the required slight movement 35 on their pivots which will insure the adjacent end holes of each block or set of holes being the same distance apart as are the holes of each block or set. By providing 40 multiple punching means for forming the

side rows of holes, the work can, of course, be carried on more rapidly than where a single punch is so employed, and in some work the employment of such multiple punching means is very desirable.

Of course, the two side rows of holes are not absolutely parallel, owing to the pivoting of the bolsters as described, but on account of the length of the bolsters and the exceedingly small arc described in their turning, the departure from exact parallelism is so inconsiderable as to be negligible. If desired, however, the bolsters could be slidingly mounted instead of pivoted and both ends adjusted simultaneously and to the same extent, as all that would be necessary to accomplish that would be to extend the shaft 59 across the machine and duplicate the gears 61, 63, and 66, the latter meshing with a suitable worm-gear on that end 45 of the bolster 24 that is now shown as pivoted.

In place of providing means for automatically adjusting the bolsters after each punching operation, manually-operated means may be employed. Such means are shown in Figs. 6 and 7. In this construction the disk 44 on the shaft 18 and the face-wheel 47 and its shaft 48 and worm 51 are dispensed with—all the balance of 50 the gearing being retained, and hence to such gearing the same reference numerals are applied. Substituted for the omitted parts are a horizontal shaft 70, a worm 71 fixed thereon, and a hand-crank 72. The worm 71 meshes with the worm-gear 52. Non-rotatably mounted on the shaft is a gage in the form of a disk 74. As shown, it is provided with an annular series of holes into any one of which a pin 73 loosely carried by the crank 72 may be inserted. Turning the crank between successive punching operations will, through the gearing set in motion thereby, cause a movement of the bolsters just as described in connection with the automatic operation, and the degree of movement required can be determined and gaged by moving the crank to a position opposite any one of the series of holes in the gage disk, whereupon the crank will be 100 locked by inserting the pin in such hole, and at each succeeding operation the crank will be again turned through a like distance and again locked in like manner.

So far as I am aware, it is broadly new with me, in connection with a machine for punching two substantially parallel rows of holes in a plate, to provide means for causing a slight relative change in the position of one of the punching means and the plate being operated upon, which is in addition to such change as is necessarily due to the ordinary travel of the plate, whereby the holes in one row are spaced apart differently than are the holes in the other row.

I therefore wish it to be understood that the claims hereinafter made are to be construed generically, my invention not being restricted to the constructions particularly 5 illustrated and described, except in so far as they are specifically claimed.

That which I claim as my invention, and desire to secure by Letters Patent, is,—

1. A plate-punching machine, comprising, 10 in combination, punching means arranged to punch two series of holes, means for operating said punching means substantially in unison, the said holes being formed by successive punching operations, and means for 15 causing the holes in one series to be spaced differently from those in the other series.

2. A plate-punching machine, comprising, 20 in combination, a movable support for the plate to be punched, punching means arranged to punch two series of holes, means for operating said punching means substantially in unison, the said holes being formed by successive operations, and means for causing the holes in one series to be spaced differently 25 from those in the other series.

3. A plate-punching machine, comprising, 30 in combination, a support for the plate to be punched, a plurality of punching means, means for actuating said punching means substantially in unison to form a plurality of series of holes in the plate, and means for moving one of said punching means between successive punching operations to cause the holes of one series to be differently spaced 35 than are the holes in the other series.

4. In a punching machine adapted to punch two substantially-parallel rows of holes in a plate intermittently moved through the machine, the combination with two punching 40 means for forming such holes and means for reciprocating the punches, of means for causing a slight relative movement between one of the punching means and the plate between successive punching operations, in addition to that due to the regular forward 45 movement of the plate, whereby the holes in one of said rows will be differently spaced than are the holes formed in the other row.

5. In a punching machine adapted to punch 50 two substantially-parallel rows of holes in a plate being moved through the machine, the combination with two punching means for forming such holes, a movable support for the dies coöperating with the said punching means, and means for reciprocating the punches, of means for slightly moving one end of said die-support and one of the punching means between successive punching operations, whereby the holes in one of said 55 rows will be differently spaced than are the holes in the other row.

6. In a punching machine adapted to punch 60 two substantially-parallel rows of holes in a plate, the combination with two punches for forming such holes and means for recipro-

cating the punches, of means for slightly changing the position of one of the punches after each punching operation, whereby as the plate is moved forward beneath the punches the holes in one of the rows will be 70 differently spaced than in the other row.

7. In a punching machine adapted to punch two substantially-parallel rows of holes in a plate, the combination with a plurality of punches for forming such holes and means 75 for reciprocating the punches, of means for automatically slightly moving one of the punches after each punching operation, whereby as the plate is moved forward beneath the punches the holes at one side of 80 the plate will be differently spaced than at the other side.

8. In a punching machine adapted to simultaneously punch holes adjacent to each side margin of a plate, said machine having a 85 reciprocating ram, the combination of a pivoted bolster beneath the ram and movable therewith, a plurality of punches carried by said bolster for forming the said holes, and means for slightly turning said bolster 90 on its pivot after each punching operation, whereby as the plate is moved forward beneath the punches the holes at one side of the plate will be differently spaced than at the other side. 95

9. In a punching machine adapted to punch two substantially-parallel rows of holes in a plate, said machine having a reciprocating head or ram, the combination of a bolster pivoted near one end beneath the said ram 100 and movable therewith, a plurality of punching means carried by said bolster for forming the said holes, the pivot of the bolster being located beneath one of said punching means, and means for slightly turning the 105 bolster on its pivot after each punching operation, whereby as the plate is moved forward beneath the punches the holes at one side of the plate will be differently spaced than at the other side. 110

10. In a punching machine adapted to punch two substantially-parallel rows of holes in a plate, the said machine having a reciprocating ram and a table, the combination of an upper and a lower bolster pivoted 115 respectively to said ram and the table, means for connecting the bolsters together, punches and dies carried by said bolsters respectively for forming the said holes, and means for slightly turning said bolsters on their pivots 120 after each punching operation, whereby as the plate is moved forward beneath the punches the holes at one side of the plate will be differently spaced than at the other side. 125

11. In a punching machine adapted to punch two substantially-parallel rows of holes in a plate, the said machine having a reciprocating ram and a table, the combination of an upper and a lower bolster pivoted 130

respectively to said ram and the table, means for connecting the bolsters together, punches and dies carried by said bolsters respectively for forming the said holes, and means for 5 slightly turning said bolsters on their pivots after each punching operation, whereby as the plate is moved forward beneath the punches the holes at one side of the plate will be differently spaced than at the other 10 side, said last-named means comprising a worm-gear on one of said bolsters and a worm coöperating therewith.

12. In a punching machine, the combination 15 with reciprocating punching mechanism comprising a bolster extending transversely of the machine and punching means supported by the bolster, of means operative between successive punching operations for moving one end of the bolster in a line approximately parallel with the line of movement of the material being punched.

13. In a punching machine, the combination 20 with reciprocating punching mechanism comprising a bolster extending transversely of the machine and punching means supported by the bolster, of means operative between successive punching operations for slightly moving the bolster in a line approximately parallel with the line of movement of the material being punched.

14. In a punching machine, the combination 25 with reciprocating punching mechanism comprising a bolster extending transversely of the machine and punching means supported on each end portion of the bolster, of means operative between successive punching operations for moving the bolster in a line approximately parallel with the line of movement of the material being punched.

15. In a punching machine comprising a 30 ram and means for reciprocating the same, the combination of two punching means each adapted to punch a line of holes in a plate as the plate is moved beneath them, means for holding said punching means movably connected to said ram, and means for slightly changing the position of one of the punching means after each punching operation to cause the holes formed by said last-named means to be differently spaced than

are the holes formed by the other punching means.

16. In a punching machine, the combination 35 of two punching means each adapted to punch a line of holes in a plate as the plate is moved beneath them, a bolster for supporting said punching means, means for vertically reciprocating said bolster, and other means for imparting a slight horizontal movement thereto between successive punching operations, such movement being in a line approximately parallel with the line of movement of the material being punched. 60

17. In a punching machine, the combination 65 of two punching means adapted to punch a line of holes in a plate as the plate is moved beneath them, a bolster for supporting said punching means, means for reciprocating said bolster and punching means, gearing connecting with said bolster for moving it slightly between successive punching operations, and means for driving said gearing, such movement being in a 70 line approximately parallel with the line of movement of the material being punched.

18. In a punching machine, the combination 75 of two punching means each adapted to punch a line of holes in a plate as the plate is moved beneath them, a pivoted bolster for supporting said punching means, means for reciprocating said bolster and punching means, gearing connecting with said bolster for turning it slightly on its pivot between 80 successive punching operations, and means for driving said gearing.

19. In a punching machine, the combination 85 of two punching means each adapted to punch a line of holes in a plate as the plate is moved beneath them, a bolster for supporting said punching means, a ram for forcing down said bolster and punching means, a rotating shaft through which said ram is reciprocated, and gearing interposed 90 between said shaft and bolster for moving said bolster slightly between successive punching operations.
